E. L. JACOBS

WRENCH

Filed April 13. 1922

Inventor

E. L. Jacobs

John H. Randolph, Jr.

UNITED STATES PATENT OFFICE.

EVELYN LEON JACOBS, OF HENRYETTA, OKLAHOMA.

WRENCH.

Application filed April 13, 1922. Serial No. 552,130.

To all whom it may concern:

Be it known that I, EVELYN L. JACOBS, a citizen of the United States, residing at Henryetta, in the county of Okmulgee and State of Oklahoma, have invented certain new and useful Improvements in Wrenches; and I do hereby declare the following to be a full, clear, and exact description of the invention, such as will enable others skilled in the art 10 to which it appertains to make and use the same.

This invention relates specifically to a tank wrench for use in the oil field when constructing bolted steel tanks.

15 The invention has for its object the provision of a wrench which will enable the work to be effected more conveniently, in less time and with the expenditure of a minimum amount of energy.

20 Other objects and advantages will be apparent and suggest themselves as the nature of the invention is understood.

While the drawings illustrate an embodiment of the invention it is to be understood 25 that in adapting the same to meet different conditions and requirements, various changes in the form, proportion and minor details of construction may be resorted to without departing from the nature of the invention.

30 Referring to the accompanying drawings forming a part of the application,

Figure 1 is an elevation of a wrench embodying the invention, parts being broken away,

35 Figure 2 is a sectional detail on the line 2—2 of Figure 1, and

Figure 3 is a sectional detail on the line 3—3 of Figure 1.

40 Corresponding and like parts are referred to in the following description and designated in the several views of the drawings by like reference characters.

The numeral 1 designates a crank brace of ordinary form provided at one end with 45 a swivel head 2 and having spaced ears 3 at its opposite end. The numeral 4 designates a rod or bar having a socket 5 detachably fitted to one end and having a fork 6 at its opposite end corresponding to the spaced 50 ears 3 of the crank brace 1. A block 7 of symmetrical form is fitted between the ears 3 and furcations 6 of the fork and is pivotally connected thereto by means of screws or

pins 8 detachably fitted to the parts 3 and 6, whereby the block 7 may be removed at will. 55 The openings, formed in the sides of the block 7 to receive the inner ends of the elements 8, extend into the block a short distance only and do not pass therethrough, hence the block is not unnecessarily weakened and the elements 8 may lie in the same plane without interfering with one another. 60 The elements 8 are threaded into the parts 3 and 6, whereby they are positively connected therewith and are capable of being readily 65 removed when required. The sides of the block 7 are of rounded form, whereby provision is had for a freedom of movement and maximum strength and durability.

A T-fitting 9 is slidable on the rod or bar 70 4 and an expansible helical spring 10, mounted on the part 4 and confined between the parts 5 and 9, normally tends to hold the fitting 9 at the limit of its upward movement on the part 4. A sleeve 11, provided 75 with an offset shank 12, is connected with the lateral nipple of the T-fitting 9 by having the shank 12 threaded therein, a clamp screw 13 securing the sleeve in the required adjusted position. A rod or bar 14 is ad- 80 justable in the sleeve 11 and is secured in the adjusted position by means of a clamp screw 15 mounted in a threaded opening formed in 85 a side of the sleeve. The lower end of the rod or bar 14 is bent laterally, as indicated 85 at 16, and is threaded to receive a socket 17 which is secured by means of a clamp screw 18. The sockets 5 and 17 are detachable and may be replaced by other sockets of different form and size. A clamp screw 19, threaded 90 into a side of the socket 5, secures the latter upon the rod or bar 4.

In the operation of the brace, the bolt and nut are held between the sockets 5 and 17 and the crank brace may be adjusted to any 95 relative angle as found most convenient and may be operated in the usual way to connect the parts. The construction is such as to enable the work to be conveniently performed in a rapid and expeditious manner and with 100 a minimum amount of effort and vexation.

What is claimed is:

A wrench having a bar provided with a laterally projecting right angular end portion integral therewith, a socket screw 105 threaded on said end portion to permit lat-

eral adjustment thereof, a sleeve slidably
adjustable along said bar and provided with
a shank, a fitting into which said shank ex-
tends, means to extensibly secure said shank
and said fitting together for adjustment to
correspond to the position of said socket, a
rod parallel to said bar and slidable in said
fitting, a socket carried by said rod to co-act
with the first mentioned socket, and an op-

erating means for the rod disposed above 10
said fitting.

In testimony whereof I affix my signature
in presence of two witnesses.

EVELYN LEON JACOBS
